UNITED STATES PATENT OFFICE

MAX M. MUNK, OF WASHINGTON, DISTRICT OF COLUMBIA

VARIABLE PITCH PROPELLER

Application filed July 10, 1931. Serial No. 550,011.

My invention relates to propellers and more particularly to aerial propellers.

Many attempts have been made to provide for a variation of the shape of a propeller during flight in order to adapt the propeller to various conditions, such as change of rate of revolution, traveling velocity, air density and the character of the maneuver which the pilot intends to execute.

None of the variable pitch propellers, as they are commonly called, have come into general use because of difficulties in their mechanical construction. The propellers have to be adjusted while under the action of very large centrifugal forces and the constructions so far proposed have their bearing surfaces loaded by the centrifugal forces. As a result, excessive friction is developed between the moving parts and it is necessary to use a large force in order to adjust the propellers.

It is an object of the present invention to provide a propeller which is adjustable during operation, all bearing surfaces of which are free from centrifugal forces.

Another object of this invention is to provide a propeller having longitudinally split blades, corresponding pairs of blade portions forming individual units balanced by themselves.

Still another object of this invention is to provide a propeller consisting of portions adjustable relative to each other by rotation about the main propeller axis.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular constructions, which

for the purpose of explanation, have been made the subject of illustration.

In the drawing like numerals refer to similar parts throughout the several views, of which

Fig. 1 represents a cross section through the center of a propeller along the main propeller axis and a pair of blades;

Fig. 2 shows a cross section through line 2—2 of Fig. 1, and

Fig. 3 is a cross sectional view through the propeller along the line 3—3 of Fig. 1.

Referring to the drawing, and more particularly to Fig. 1 thereof, the main body of the propeller is shown as being split or divided into two portions, 1 and 2. The front portion 1 is keyed to the driving shaft 3 and secured thereto by means of a washer 4 and lock nut 5 which presses the front portion of the propeller against the collar 6 of the shaft 3. The propeller portion, 1, consists of the hub 1a, the blade portions 1b and 1c, all three parts being formed integrally of light metal.

On the rear extension of the hub 1a is rotatably mounted the hub 2a of the propeller portion 2, which hub is formed integrally with the two blades portions 2b and 2c. A ring 7, fastened to the hub 1a by means of pins 8, prevents any axial motion between the propeller portions 1 and 2. Between the two rear extensions of the hubs 1a and 2a is inserted a bearing or flanged sleeve 9 interlocking with the extensions 1a and 2a by means of spiral keys 9a and 9b fitting into corresponding spiral grooves of the hub extensions. The spirals 9a are right handed and the spiral keys 9b are left handed. All parts so far mentioned rotate with the propeller and its shaft.

The flange of the sleeve 9 is held in axial position by a nut 10 which may be screwed along the outside thread of the bearing 11 by means of a hand crank 12, the shaft 13 and the cog wheel 14 in mesh with the nut 10. The ring 15 attached to the nut 10 by means of bolts, 16, eliminates any axial motion between the nut 10 and the sleeve 9, without interfering with the rotation of the

sleeve relative to the stationary nut when the hand crank 12 is turned.

In order to increase the rigidity of the propeller, the two adjacent parts of the blade 5 may be dovetailed as shown at 16.

When the hand crank is turned the nut 10 is rotated and moves along the sleeve 9 in an axial direction and in consequence of the opposite inclination of the spiral keys of 10 the bearing the parts 1 and 2 of the propeller turn through a small angle relative to each other and adjustment is thereby effected.

The cross section of the propeller shown 15 in Fig. 3 through the two portions of the blade shows the effect of the adjustment on the common cross section. The dotted section of one blade portion is moved to the full line position whereby the aerodynamic pitch and the effective blade area is changed.

20 It will now be realized that there has been disclosed a principle relating to the changing of pitch of a propeller, which can be effected without experiencing difficulties resulting from large bearing pressures caused 25 by centrifugal forces.

While I have shown and described the preferred embodiment of my invention, I wish it to be understood that I do not confine myself to the precise details of construction 30 herein set forth, by way of illustrations, as it is apparent that many changes and variations may be made therein, by those skilled in the art, without departing from the spirit of the invention, or exceeding the scope of 35 the appended claims.

What is claimed is:

1. A propeller comprising a blade divided 40 longitudinally into two parts, one of said parts being movable with respect to the other about the axis of the propeller shaft.

2. A propeller comprising a blade having a plurality of sections, one section of the blade being adapted to slide relative to another section about the propeller axis.

3. A propeller blade consisting of two sections adapted to slide relative to each other about the main propeller axis.

4. A propeller comprising a blade having two sections formed with hub extensions, a bearing mounted between the extensions and means adapted to impart motion to said bearing whereby the propeller blade sections slide relative to each other about the main propeller axis.

5. A propeller comprising a blade having two sections formed with integral hub extensions, a bearing mounted between the extensions and interlocked therewith, and means adapted to impart motion to said bearing whereby the propeller blade sections are rotated relative to each other about the axis of the propeller shaft.

6. A propeller comprising a blade having two sections formed with integral hub extensions having grooves formed therein, a bear-

ing mounted between said extensions and interlocked therewith, and means adapted to impart longitudinal movement to said bearing whereby the propeller blade sections are rotated relative to each other about the axis 70 of the propeller shaft.

7. A propeller comprising a blade having two sections formed with integral hub extensions, said extensions having grooves formed therein, a bearing mounted between the extensions, means to interlock the bearing with the hub extensions comprising keys adapted to fit into the grooves formed in the hub extensions, and means adapted to impart motion to said bearing whereby the propeller blade sections are rotated relative to each other about the axis 80 of the propeller shaft.

8. A propeller comprising a blade having two interlocked sections formed with integral hub extensions, said extensions having spiral grooves formed therein, a bearing mounted between the extensions, means to interlock the bearing with the hub extension comprising spiral keys adapted to fit into the spiral grooves formed in the hub extensions, and means adapted to impart longitudinal and rotary motion to said bearing whereby the propeller blade sections are rotated relative to each other about the axis of 90 the propeller shaft.

In testimony whereof I affix my signature.
MAX M. MUNK.
